(57) **CLAIM**

We claim the ornamental design for a skate, as shown and described.

DESCRIPTION

FIG. 1 is perspective view of a skate showing our new design;

FIG. 2 is first side view thereof;

FIG. 3 is front elevation view thereof;

FIG. 4 is a rear elevation view thereof;

FIG. 5 is an opposite side view of FIG. 2 thereof;

FIG. 6 is a bottom plan view thereof; and,

FIG. 7 is a top plan view thereof.

The broken lines do not form part of the claimed design.
